UNITED STATES PATENT OFFICE

2,557,699

LINOLEUM SCRIBER

William Silver, Roxbury, Mass.

Application May 10, 1946, Serial No. 668,715

3 Claims. (Cl. 33—41)

1

This invention relates to an improved linoleum scribe used by a workman when laying linoleum.

An object of the invention is to provide an improved linoleum scribe which may be used for both under scribing and over scribing.

Another object of the invention is to provide an improved linoleum scribe including a longitudinally slotted body having means for supporting a scribing needle and cutting knife at one end, and a block adjustably supported along said slots having a forwardly extending flexible arm provided with a depending V-shaped guide foot on its extremity.

A further object of the invention is to provide an improved linoleum scribe which may be provided with a pair of adjustable spaced scribing needles whereby varying widths of feature strips of linoleum may be scribed and cut.

Another object of the invention is to provide an improved linoleum scribe having a fixed scribing needle at one end and an adjustable extension bar at the opposite end of said scribe body for supporting a second needle, whereby circles of varying diameters may be scribed and cut.

Another object of the invention is to provide an improved lockable scribing needle for linoleum scribes.

Other objects of the invention will appear as the description proceeds.

In the accompanying drawings which form a part of this application,

Figure 1 is a perspective view of the improved linoleum scribe as used for under scribing;

Figure 2 is a longitudinal sectional view of the scribe with guide foot supporting blocks removed for under scribing when cutting the linoleum to provide a flush joint;

Figure 3 is a vertical sectional view through the improved adjustable locking needle;

Figure 4 is a plan view of the forward end of the scribe body being partly broken away and in section to show a scribing needle and cutting knife held in position by the locking set screws;

Figure 5 is a bottom plan view of the adjustable block with flexibly supported guide foot;

Figure 6 is an enlarged bottom plan view of the flexible slotted guide arm for the supporting guide foot with scribing needle in position in said slot;

Figure 7 is a perspective view of the improved linoleum scribe showing the same when used for over scribing;

Figure 8 is a longitudinal sectional view of a portion of the scribe with the scribing needle in position for scribing close to the edge of a piece of linoleum;

2

Figure 9 is a side elevation of the scribe showing the same in position to scribe close to a wall;

Figure 10 is a detail view showing the end of the scribe with extension bar connected therewith and supporting a cutting blade or pin for cutting various sizes of circles, and

Figure 11 is a plan view of the scribe with square employing a pair of adjustably spaced pins for cutting or scribing various widths of feature strips of linoleum.

Like characters of reference are used throughout the following specification and the accompanying drawings to designate corresponding parts.

15 In carrying out the invention, there is provided an improved linoleum scribe having an elongated body generally denoted by the reference numeral 1, and being tapered at its forward end to provide the pointed head 2, through which the spaced 20 openings 3 and 4 are formed for respectively receiving the scribe pin 5 and the cutter blade 6, the same being securely held in place by means of the set screws 7 and 8, respectively.

The body 1 of the scribe is formed with a 25 longitudinally extending slot 9, which terminates at its inner end with the rounded aperture 10, the purpose of which will be hereinafter described. A supporting base will be secured transversely to and below the inner end of said body 1, to hold the same in spaced relation from the upper surface of the linoleum when the same is being scribed or cut.

Oppositely disposed guide surfaces will be provided in the under surface of the body 1 of the 35 scribe, and will serve to guide the block 13 which supports the forwardly extending flexible arm 14, said arm being formed with a longitudinal slot 15 and provided with an integrally formed depending V-shaped guide foot 16 on its forward extremity. The longitudinally adjustable block with the V-shape guide foot is supported for longitudinal adjustment along the slot 15 by means of the set screw 17 which is provided with the enlarged knurled head 18, which may 40 be moved through the said rounded aperture 10 when the block is being removed from the scribe body.

In Figure 1 of the drawings, the scribe body 1 is shown with the scribing needle 5 in the forward opening 3 in position to under scribe a piece of linoleum (not shown) when inserted between the lower surface of the scribe body 1 and the upper surface of the flexible arm 14. The scribe may be pulled along the edge of the linoleum to 55 mark the same so that it may be cut to form a

flush joint with an adjacent piece of linoleum. In Figure 3 of the drawings, there is illustrated a vertical sectional view through the improved ball locking scribe needle, said needle being indicated by the reference numeral 19 and being vertically supported through the externally threaded supporting member 20 formed with the laterally extending head 21 on its lower end. A guide member 22 being formed with a central aperture is adapted to support the supporting member 20 with the head 21 in contact with its under surface, and to be secured thereto by means of the threaded nut 23. The locking nut 24 is adapted to be threaded upon the upper end of the externally threaded supporting member 20 and to be formed with an internal conical seat 25 in which a single ball bearing 26 will be disposed to cooperate with the conical upper end 27 of the supporting member 20, whereby when said locking nut 24 is threaded or turned down on the supporting member 20 the ball bearing 26 will be cammed into engagement between the conical upper end 27 of the supporting member and the adjacent wall of the conical seat 25 to lock the pin or needle 19 within its supporting member. The improved ball locking needle will be adjusted for longitudinal movement along the slot 9 formed through the body 1 of the scribe and will be held in adjusted position along said slot by clamping action between the nut 23 and the upper surface of the guide member 22, as clearly shown in the drawings.

In Figure 2 of the drawings, the scribe is illustrated with the block 13 removed and the ball locking needle 19 in position within the slot 9, and a piece of linoleum 28 supported upon a wood strip 29 placed adjacent the piece of linoleum 30, whereby when the piece of linoleum 28 is scribed by the needle 19 and the end cut therefrom, a flush joint will be provided between the two pieces of linoleum 28 and 30.

In Figure 7 of the drawings, there is illustrated the needle 19 placed at the inner end of the scribe body 1 and a cutting knife 6 supported in the outer end in position to cut the piece of linoleum 31, which has been placed in position to cut a circle therefrom.

In Figure 10 of the drawings, there is illustrated the body 1 of the scribe supporting an extension bar 32, which supports the scribing needle 33 at its outer extremity whereby circles of any size may be scribed.

In Figure 11 of the drawings, there is illustrated the improved scribe 1 shown in connection with a T-square 33 and a pair of spaced ball locking scribing needles, said T-square being placed on a flat side of a piece of linoleum 34 with the needles 19 set the desired distance apart so that as the scribe is drawn along the body of the T-square 33, the desired width of a feature strip or piece of linoleum may be scribed, and later cut. Obviously, varying widths of strips may be scribed and cut by spacing the needles and cutting blade the desired distance apart.

In Figure 8 of the drawings the improved ball locking needle is shown on the scribe body 1 with the scribe placed at the edge of a strip of linoleum 35 to scribe the same when the strip is to be cut from the edge of the piece of linoleum.

In Figure 9 of the drawings, the scribe body 1 is shown supporting the ball lock needle in position with the scribe body in contact with a wall of a room in position to scribe a line along the

piece of linoleum 36 which is placed with its edge in contact with the said wall.

The depending V-shaped guide foot 16 is clearly illustrated in Figures 5 and 6 of the drawings, and is thus formed so that the scribe may be used when scribing around a corner or for making semi-circular scribing to cut out small pieces of linoleum. The slot 15 formed in the flexible arm 14 is provided so that the scribing needle may be set either close to the said foot 16 or at a point spaced therefrom the desired distance.

From the foregoing description, it will be apparent that there has been devised a highly efficient form of linoleum scribe which may be used for under scribing and also for over scribing, and which may be used for scribing circles or strips of various sizes, and for scribing around corners and in close quarters.

While the preferred embodiment of the instant invention has been illustrated and described, it will be understood that it is not intended to limit the scope of the invention thereto, as many minor changes in detail of construction may be resorted to without departure from the spirit of the invention.

Having thus described my invention what I claim as new and desire to secure by Letters Patent of the United States is:

1. A linoleum scribe comprising an elongated inverted channel member constituting a body, a central longitudinally extending slot in said body, a reduced head on one end of the body, means for locking tools in vertically adjustable positions in the head, a transverse support block attached to the opposite end of the body, a guide block slidably incunted longitudinally on the undersurface of the body, a flexible arm extending forwardly from the bottom of the block, a longitudinal slot in said arm in vertical alignment with the slot in the body, a bearing surface on the extending end of said arm and means for locking said guide block to said body in adjusted positions.

2. A linoleum scribe comprising an elongated inverted channel member constituting a body, a longitudinally extending slot in said body, a reduced head on one end of the body, a straight transverse edge on the other end of said body, longitudinally spaced vertical openings in said head, transversely disposed means in said head for removably and adjustably locking a cutter blade in the openings, a transversely disposed support block on the straight end of the body, means for vertically and longitudinally adjusting a scribe needle in said slot, said last-recited means including an externally threaded supporting member vertically disposed through said slot, a laterally extending head on one end of the supporting member slidably engaged on the under surface of the body, a central longitudinally extending scribe needle receiving opening in said supporting member, a locking nut received on said supporting member and seated on the upper surface of the body for clamping coaction with the head of the supporting member, a conical end on said supporting member, a locking nut having an external conical seat received on the conical end of said supporting member, and a cam locking member received in said seat for locking a scribe needle in the supporting member, said cam locking member including a ball bearing.

3. In combination with a scribe having a body with a longitudinally extending slot therein, means for vertically and longitudinally adjusting

a scribe needle in said slot, said means including an externally threaded supporting member vertically disposed through said slot, a laterally extending head on one end of the supporting member slidably engaged on the under surface of the body, a central longitudinally extending scribe needle receiving opening in said supporting member, a locking nut received on said supporting member and seated on the upper surface of the body for clamping coaction with the head of the supporting member, a conical end on said supporting member, a locking nut having an external conical seat received on the conical end of said supporting member, and a cam locking member received in said seat for locking a scribe needle in the supporting member, said cam locking member including a ball bearing.

WILLIAM SILVER.
